COMBINATION CAN PUNCTURER AND HANDLE

Charles F. Kaemmerlen and Elijah J. Willis,
Morehead City, N. C.

Application May 5, 1936, Serial No. 78,048

3 Claims. (Cl. 164—120)

This invention relates to a combination can puncturer and handle, and has for the primary object the provision of a simple and inexpensive device of this character which may be easily and quickly adapted to a can and actuated to puncture spaced holes in the top of the can, one of which may be employed for discharging the contents of the can while the other hole admits air into the can to facilitate the flow of the contents and also the device provides a convenient means for handling the can for pouring the contents or for carrying the can with ease.

With these and other objects in view, this invention consists in certain novel features of construction, combination and arrangement of parts to be hereinafter more fully described and claimed.

For a complete understanding of our invention, reference is to be had to the following description and accompanying drawing, in which

Figure 1 is a side elevation illustrating a combination can puncturer and handle constructed in accordance with our invention and showing the same on a can.

Figure 2 is a top plan view illustrating the device.

Figure 3 is a perspective view showing the device applied to the can prior to puncturing the latter and illustrating the use of the device as a handle for the can.

Figure 4 is a bottom plan view illustrating the device.

Figure 5 is a fragmentary side elevation showing the device adjusted to accommodate a can of a size smaller than the size of the can shown in Figure 1.

Figure 6 is a perspective view illustrating a modified form of our invention.

Referring in detail to the drawing, the numeral 1 indicates a bar bent adjacent one end to form a finger piece 2. The other end of the bar is bent at right angles thereto and cut away to form a shouldered jaw 3 having a limited resiliency. Pivoted to the bar 1 adjacent the handle 2 is a can engaging element 4 having each end offset and shouldered, as shown at 5. The pivot of the can engaging element 4 is located closer to one end than to the other so that the device may be readily adapted to large and small cans.

50 A bracket 6 is secured to the bar 1 adjacent the pivot of the can engaging element 4 and has pivoted thereto a can puncturing means 7 of substantially T-shaped formation. The can puncturing means 7 includes a leg portion 8 which is pivoted to the bracket 6 and a head portion 9

having its ends bent at right angles and pointed to provide can penetrating elements 10. The bar is overlapped by the head and leg portions 9 and 8 with the can penetrating elements disposed at opposite sides of the bar. A coil spring 11 is secured to the leg portion 8 and to the bar and acts to urge the head portion in the direction of the bar.

In operation, the bar 1 is brought into engagement with the top of a can, the penetrating elements also contacting the top of the can. The can engaging element engages one side of the can under the usual rim flange of the can. Pressure is applied to the bar causing the jaw 3 to snap under the rim flange at an opposite side of the can from the can engaging element 4. Pressure is then applied to the head 9, causing the can puncturing elements 10 to penetrate the can, as shown in dotted lines in Figure 1. After the penetration of the can, pressure is applied to the free end of the leg portion 8 disengaging the penetrating elements 10 from the can and at the same time the handle 2 is gripped whereby the can may be tilted for pouring the contents with the latter vented to the atmosphere. The pouring of the contents from the can may be from either of the openings formed therein. The device may be left upon the can if the latter is not entirely emptied of its contents and when pressure is released from the leg portion 8 the spring 11 acts to return the penetrating elements 10 into the holes closing said holes to prevent the entrance of foreign matter into the can.

Referring to our modified form of invention, a can puncturing means 11' is pivoted to the bracket 6 of the bar 1 and is of a type whereby openings may be punctured one at a time in the top of the can and consists of a pair of members 12 including parallel portions 13 forming a handle and also includes diverging portions 14 disposed in opposite directions with respect to the bar 1 and having their free ends bent at right angles and pointed to form penetrating elements 15. The penetrating elements 15 may be moved simultaneously or either independently of the other. The parallel portions 13 are offset, as shown at 16, to form a seat for one end of the spring 11.

In this form of our invention it is attached to a top of a can in a manner similar to the heretofore described form and by placing pressure on the diverging portions 14 openings may be simultaneously punctured in the top of the can or if it is desired to puncture openings singularly, pressure is first applied to one of the diverging por-

tions and then the other. To raise the penetrating portions from the openings pressure is applied to the parallel portions 18.

Having described the invention, we claim:

- 5 1. A device of the character set forth comprising a bar to extend across a top of a can, a resilient jaw at one end of the bar to engage with one side of the can, a can engaging element pivoted to said bar and having its ends offset, either 10 of which is adapted to engage with the can to cooperate with the jaw in securing the bar to the can, the pivot of said can engaging member being located closer to one end thereof than the other to permit application of the bar to cans of 15 different sizes, and can penetrating means carried by said bar.
2. A device of the character set forth comprising a bar to extend across a top of a can, a resilient jaw at one end of the bar to engage with one side of the can, a can engaging element pivoted to said bar and having its ends offset, either 20 of which is adapted to engage with the can to cooperate with the jaw in securing the bar to the can, the pivot of said can engaging member being 25 located closer to one end thereof than the other

to permit application of the bar to cans of different sizes, a finger piece formed on said bar, a bracket secured to said bar, and a spring pressed can penetrating means pivoted to said bracket.

3. A device of the character set forth comprising a bar to extend across a top of a can, a resilient jaw at one end of the bar to engage with one side of the can, a can engaging element pivoted to said bar and having its ends offset, either 10 of which is adapted to engage with the can to 15 cooperate with the jaw in securing the bar to the can, the pivot of said can engaging member being located closer to one end thereof than the other to permit the application of the bar to cans of different sizes, a finger piece formed on said bar, 15 a bracket secured to said bar, a member pivoted to said bracket and including a leg portion and a head portion, said head portion having its ends bent at right angles and sharpened to form 20 penetrating elements, and a spring acting on the leg portion and located between the latter and the bar.
